(57) **CLAIM**

The ornamental design for a front portion of automobile, as
shown and described.

DESCRIPTION

FIG. 1 is a front perspective view of a front portion of
automobile showing our new design;

FIG. 2 is a rear perspective view thereof;

FIG. 3 is a right-side view thereof, with the left-side being
a mirror image;

FIG. 4 is a top view thereof;

FIG. 5 is a front view thereof; and,

FIG. 6 is a rear view thereof.

The claimed design is indicated by the relatively dark
portions in FIGS. 1-6, while the relatively light portions
thereof are environmental and form no part of the claimed
design.
